L20-42

OR D 6,955

UNITED STATES PATENT OFFICE.

CHARLES H. SHACKFORD AND MARTIN V. CAMPBELL, OF SYRACUSE, N. Y.

DESIGN FOR ADVERTISING-FRAMES.

Specification forming part of Design No. 6,955, dated October 7, 1873; application filed September 15, 1873.
[Term of Patent 3½ years.]

To all whom it may concern:

Be it known that we, CHARLES H. SHACKFORD and MARTIN V. CAMPBELL, of Syracuse, New York, have invented a Design for Advertising-Mirrors, of which the following is a specification:

The nature of our invention relates to an improvement in designs for advertising-mirrors; and it consists in the arrangement and configuration of parts, which will be more fully described hereafter, whereby a beautiful and elegant advertising-frame is produced.

The accompanying photographic illustration represents our invention.

a represents the frame, made oblong vertically, and having the ornamental head or cap piece *c*, and ornamental sides and bottoms *e*, as shown. This frame is divided into sections, in which are placed an oblong mirror, *d*, and advertising-placards. The sections *g* extend up the side of the mirror, and are all made of uniform size and shape. The three sections placed above the top of the mirror are

larger than the ones *g*, and have rounding tops, the two corner ones, *i*, being of the same shape and size, and smaller than the central one, *l*. Attached to the bottom of the frame is a row of pigeon-holes, *o*.

The sizes of the various parts above described will of course vary in proportion to the size of the frame *a*, being made larger or smaller, as may be desired.

Having thus described our invention, we claim—

The design for an advertising-mirror consisting of the frame *a c e*, mirror *d*, sections *g i l*, and pigeon-holes *o*, when arranged substantially as shown and described.

In testimony that we claim the foregoing we have hereunto set our hands this 12th day of September, 1873.

CHARLES H. SHACKFORD.
MARTIN V. CAMPBELL.
